(57) **CLAIM**

The ornamental design for a multifunction printer, as shown and described.

DESCRIPTION

FIG. 1 is a perspective view of a multifunction printer showing our new design;

FIG. 2 is a front view thereof;

FIG. 3 is a right side view thereof;

FIG. 4 is a rear view thereof;

FIG. 5 is a left side view thereof;

FIG. 6 is a top plan view thereof; and,

FIG. 7 is a bottom plan view thereof.

The broken lines immediately adjacent the shaded areas represent the bounds of the claim, while all other broken lines are directed to environment and are for illustrative purposes only; the broken lines form no part of the claimed design. In addition, the unshaded surfaces directly adjoining the solid line claimed edge form no part of the claimed design.
